SPOT GLUE APPLICATOR FOR CARTON
MAKING MACHINES

Henry V. H. Stoever, Jr., Durham, N. C., assignor
to The American Tobacco Company, Durham,
N. C., a corporation of New Jersey

Application December 3, 1948, Serial No. 63,426

9 Claims. (Cl. 91—50)

1

This invention relates to carton making machines and more particularly to an improved apparatus for applying adhesive to parts of a carton blank as it is fed to the former.

In the manufacture of cartons in certain types of machines the blanks are cut to the proper shape and a pile of the blanks placed at the feed end of the machine. Means are provided for feeding the blanks singly through the machine. As each blank is fed from the stack, adhesive is applied to parts of it and it is then fed to a former. In certain machines now in use the adhesive applying mechanism is complicated and slows down the speed at which the machine may be operated.

In the present invention I provide a simple mechanism for applying adhesive to parts of carton blanks. The mechanism is capable of operating at a higher speed than the adhesive applying mechanism heretofore used and therefore permits the machine to operate at a higher speed with a greater output.

In carrying out the invention I provide a pair of rolls rotating above and below the space over which the portion of the carton to which the adhesive is to be applied is fed. Each roll is provided with a segment of larger diameter than the remainder of the roll and the rotation of the rolls is timed to bring these segments into registration as the carton passes between them. The upper roll, which is the adhesive applying roll, is arranged adjacent a series of rolls, one of which is arranged in the adhesive container so that upon rotation of the rolls a film of adhesive is applied to their peripheries. The segment on the upper roll is, at one point of its revolution, tangent to the last of the series of rolls and a layer of adhesive is applied to it as the surface of the segment engages the surface of this roll. Upon further revolution, as the carton passes between the registering segments of the upper and lower rolls, this adhesive is applied to the desired portion of the carton blank.

The drive shaft of the lower, or pressure, roll is provided with a clutch and I provide mechanism by means of which this clutch is disengaged upon interruption of the feed of the blanks. This prevents the segments of the two rolls from registering with each other in the absence of a carton blank which would result in the application of adhesive to the surface of the pressure roll.

In the accompanying drawings I have shown one embodiment of the invention. In this showing:

Fig. 1 is an end elevation of the apparatus;
Fig. 2 is a side elevation;

2

Fig. 3 is a plan view;

Fig. 4 is a detailed, sectional view on line 4—4 of Fig. 3;

Fig. 5 is a plan view of the carton blank; and

5 Fig. 6 is a detailed view of a portion of one of the conveyor chains.

Referring to Fig. 5 of the drawings, the carton blank B consists of a bottom 1, front and rear walls 2 and 3, a top 4 and a closing flap 5. End walls 6 extend from each end of the bottom wall and sealing flaps 7 are arranged on the ends of the front and rear walls. The present invention is directed to mechanism for applying adhesive to the carton blank at the points 8. The 10 carton blank is then fed to a former where it is folded along the scored lines 9 between the various wall sections with the sealing flaps 7 on the insides of the end walls 6 and the adhesive activated to cause these sealing flaps to adhere to the end walls.

Mechanism for forming the carton blanks is known and the present invention is directed solely to the adhesive applying mechanism. The machine comprises a table 10 supported on a suitable frame and provided with a pair of slots 12 adjacent each side to receive conveyor chains 14. At suitable intervals the conveyor chains are provided with upstanding ears 16 (see Fig. 6). Means, heretofore known, are employed for feeding the individual carton blanks B from a stack (not shown) to the left of the apparatus in Fig. 30 2 of the drawings to the conveyor chains and the ears 16 engage the rear edges of the blanks to propel them through the apparatus.

35 As shown in Figs. 2 and 3, the conveyor chains pass over sprockets 18 at the inlet end of the machine mounted on a shaft 20. On the operative flight, the chains are substantially flush with the table with the ears 16 extending upwardly beyond the plane of the table. Near the end of the operative flight the chains pass over sprockets 22 on a shaft 24 and then recede from the plane of the table. The chains pass over sprockets 26 arranged on a shaft 28 which is supported in a bracket 30 carried by the frame of the machine, the position of the sprockets 26 being slightly below the plane of the table as shown. From the sprockets 26 the chains pass under sprockets 32 which are mounted on a shaft 34. Shaft 34 is 40 driven as hereinafter described to drive the feed chains. From the sprockets 32 the chains pass over guide sprockets 36 and thence to the sprockets 18 at the end of the machine.

45 The adhesive is applied at the points 8 at each side of the carton blank on the upper side as the

blank passes through the apparatus and for the purpose of supporting the adhesive containers and the adhesive applying mechanism, I provide an upper frame member 38. At the rear of this frame member, there is a shaft 40 extending entirely across the apparatus. This shaft is provided with a sprocket 42 receiving a chain 44. Chain 44 also passes over a sprocket 46 on a driven shaft 48. An idler sprocket 50 may engage the chain for the purpose of adjusting its tension. The shaft 40 carries a kick-off device 52 by means of which the cartons are fed from the adhesive applying mechanism to the next section of the machine where the former (not shown) is arranged.

At each side of the machine I support a suitable adhesive tank 54 on the upper frame 38. A roll 56 is mounted on a shaft 58 within the tank and is adapted to dip into the adhesive and obtain a coating of the adhesive on its outer cylindrical surface. This roll in turn contacts with a roll 60 mounted on a stub shaft 62. Arranged in front of the tank is a stub shaft 64 carrying the adhesive applying roll 66. The shafts 58, 62 and 64 may be supported in suitable brackets 68. As shown in Fig. 4, the roll 66 is spaced from the roll 62 but it is provided with a segment 68 whose surface is tangential to the surface of the roll 62. This segment is also provided with raised portions 70 corresponding to the size and shape of the two portions of adhesive 8 applied to each end wall as shown in Fig. 5 of the drawings.

As shown, the segment 68 travels tangentially to the surface of the table and at the point where it passes the plane of the table, the table is provided with an opening 72. Pressure rolls 74 are mounted on shaft 76 beneath the table and each of the pressure rolls is provided with a segment 78 which, when in the upper position shown in Fig. 4 of the drawings, registers with the segment 70.

Shaft 84 which carries the sprockets driving the conveyor chains also carries a sprocket 80 which receives a chain 82 passing over a sprocket 84 on a drive shaft 86. Shaft 76 on which the pressure rolls 74 are mounted is driven by a chain 88 passing over a sprocket 90 on the shaft 76 and over a sprocket 92 on a shaft 94. The shaft 94 is driven from shaft 86 by a chain 96 passing over a sprocket 98 on shaft 86 and a sprocket 100 on shaft 94.

Each of the shafts 58 is provided with a pinion 102 meshing with pinions 105 on shafts 108. Shafts 64 are provided with gears 104 meshing with pinions 106 on shafts 108. Shafts 62 are provided with gears 109 meshing with pinions 102. The shafts 58, one at each side of the machine, are driven by chains 110 passing over sprockets on these shafts and over sprockets on the shaft 40 (see Fig. 3).

Means are provided for disconnecting the drive of shaft 76 and therefore the rotation of the pressure roll if the feed of cartons is interrupted. As shown, arms 114 are secured to a rock shaft 116 mounted over the table. These arms are provided with rounded end portions formed by rollers 112 which ride on the carton blanks as they are fed through the apparatus. The end of the rock shaft carries an arm 120 having a link 122 connected to its other end. Link 122 is connected to a pivoted lever 124 intermediate its ends. The lever is pivoted at 126 in a bracket 128 mounted on the frame of the machine. This lever, at its outer end, is provided with a trip plate 204 which controls pawl 130 in a manner hereinafter de-

scribed to disengage clutch member 132. The table is provided with openings beneath the rollers 112 and in the absence of a carton, these rollers drop into this opening, swinging shaft 116 in a clockwise direction in Figs. 2 and 4 of the drawings and thus depressing the free end of the lever 124 to disengage clutch 132.

The apparatus may also be provided with a suitable embossing device when desired. Thus, where a company has several factories in which a product may be packed and desires some means of ascertaining at which factory a carton was packed, a code indication of some character indicated at C in Fig. 5 may be stamped on each carton. Such an embossing device is represented generally at 134 and is adapted to be depressed as each carton blank passes over it to imprint or emboss the code character C on the carton. It is actuated by a rocker arm 136 pivotally mounted on a bracket 138 on the frame of the machine. The lever 136 carries a cam roller engaging a cam 140 on shaft 142. The shaft 142 is provided with a sprocket 144 which receives a chain 146. This chain passes over a sprocket on the drive shaft 86 to drive it.

As shown in Fig. 4 of the drawings, the clutch operating lever 124 may be connected to an arm 148, the lower end of which is provided with a yoke 150 which straddles the shaft 142. Shaft 142 is provided with a cam 149 having two concentric portions 151 and 153. This cam engages a roller 155 carried by arm 148. When the roller is on the portion 151 of the cam, disengagement of the clutch in the manner heretofore described is prevented, but, in the absence of a carton, the clutch is disengaged when the roller engages portion 153 of the cam, just before the segments 78 reach their operative positions. Fingers 157 are loosely mounted in a bracket in the path of the carton blanks at the inlet end of the apparatus. As the end blank passes the fingers they fall into engagement with its rear edge to prevent it from moving backward.

Shaft 94 may be provided with a brake 152 which is engaged by a brake band 154 to stop the rotation of the shaft when the clutch 132 is disconnected.

Suitable guide fingers 156 may be arranged over the table and adapted to yieldingly engage the surface of the carton blanks. These guide fingers are supported in a suitable bracket 158 carried by threaded rods 160.

Trip plate 204 carries a projection 205 which engages a recess 206 in pawl 130 beyond its pivot. The member 132 is secured to shaft 94 by a set screw or the like. Pawl 130 is carried by a disc 202 which is carried by a sleeve 207 (see Fig. 1) surrounding the shaft 94. Sprocket 100 is also carried by this sleeve.

The operation of the device will be apparent from the foregoing description. As the carton blanks B are fed to the apparatus, the rear edge of the blank is engaged by one of the ears 16 on each of the conveyor chains 14. The carton is thus propelled through the apparatus, from left to right in Fig. 2. As it passes the code device 134, the suitable code symbol C is embossed on the bottom of the box, the code device 134' being raised and lowered by the cam 140. As long as the blanks are properly fed through the machine, the free end of the lever 124 remains in raised position with the clutch 132 engaged. Shaft 76 carrying the pressure roll 74 is thus rotated and the machine is so timed that the segments 78 and 70 come into registry at the opening 72 in

the table. The raised portions 70 on segments 68 then apply the adhesive to the end walls of the carton blank as indicated at 8 in Fig. 5 of the drawings. The adhesive is received on the raised portions 70 upon each rotation of the adhesive applying rolls when they contact with the edge of the roller 60. The cartons continue to travel toward the rear of the machine as the ears 16 do not recede below the plane of the table until after they have passed the vertical plane of the pressure roll and the adhesive applying roll. At that point the kick-off mechanism 52 engages a portion of the carton blank and feeds it to the former (not shown).

In the absence of a blank on the table at the point where the rolls 112 are mounted, these rolls move downwardly through the openings arranged at that point in the table, swinging the rock shaft 116 to depress the free end of the lever 124. With the lever thus depressed when cam roller 155 rests on low portion 153 of cam 149, projection 205 engages recess 206 of pawl 130 to rock the pawl out of driving engagement with clutch member 132. This disconnects the drive to shaft 76. Brake 152 immediately stops the rotation of this shaft. In the absence of such provision, if the pressure roll 74 were permitted to rotate to bring segment 78 into registration with segment 68 and there was not a carton blank in the space 72, the adhesive would be applied to the surface of the segment 78. Then upon resumption of proper feed of carton blanks, adhesive would be applied to a blank on the opposite side from where it should normally be applied and there would be adhesive on the outside of the carton when the carton was completed.

As stated above, an important feature of the invention is that the simplicity of the adhesive applying mechanism permits it to be operated at a higher rate of speed than similar mechanism heretofore employed and therefore permits the entire machine to be speeded up.

I claim:

1. Apparatus of the character described comprising means for conveying blanks, an adhesive applying roll over the path of travel of the blanks, the roll having a segment traveling tangentially to the path of travel of the blank, a pressure roll beneath the path of travel of the blank, the pressure roll having a segment traveling tangentially to the path of the blank, drive means to cause the two segments to contact opposite sides of the blank at the same time, and means controlled by the feed of blanks for interrupting the drive of the pressure roll when a blank is not being fed through the machine to arrest the movement of the pressure roll before the segment reaches a position opposite the segment of the adhesive applying roll.

2. Apparatus of the character described comprising a conveyor for conveying blanks, an adhesive applying roll over the path of travel of the blanks, the adhesive applying roll having a segment traveling tangentially to the path of travel of the blanks, a pressure roll beneath the path of travel of the blanks, the pressure roll being provided with a segment having a path of travel tangentially to the path of the blanks, means for rotating the rolls, a clutch in the drive of the pressure roll, and a tripping member in the path of the conveyor connected to the clutch to disengage the clutch upon absence of a blank from the conveyor.

3. In an adhesive applying apparatus compris-

ing a conveyor to convey carton blanks, an adhesive applying roll arranged over the path of the carton blanks and having a portion adapted to contact with the upper face of a carton blank, a pressure roll beneath the path of the conveyor, the pressure roll having a portion adapted to contact with the under side of the carton blank and means for rotating the rolls, in combination, mechanism for interrupting the rotation of the pressure roll in the absence of a blank on the conveyor, said mechanism comprising a roller normally resting on the blank passing over the conveyor, a clutch in the drive of the pressure roll, and connections between the roller and the clutch to disengage the clutch upon lowering of the roller due to the absence of a blank.

4. Adhesive applying mechanism comprising a conveyor to convey carton blanks, an adhesive applying roll arranged over the path of the conveyor, the adhesive applying roll being provided with a segment adapted to contact a carton on the conveyor, a pressure roll arranged beneath the conveyor, the pressure roll being provided with a segment adapted to contact the under side of the carton blank, drive means for the adhesive applying roll, drive means for the pressure roll, a clutch to connect the pressure roll drive means to a source of power, and a tripping member in the path of the conveyor connected to the clutch to disengage the clutch upon absence of a blank from the conveyor.

5. Adhesive applying mechanism comprising a conveyor to convey carton blanks, an adhesive applying roll arranged over the path of the conveyor, the adhesive applying roll being provided with a segment adapted to contact a blank on the conveyor, a pressure roll arranged beneath the conveyor, the pressure roll being provided with a segment adapted to contact the under side of the carton blank, drive means for the adhesive applying roll, drive means controlled by the feed of blanks for the pressure roll, a clutch in the pressure roll drive means, and means for disconnecting the clutch in the absence of a carton blank on the conveyor.

6. Adhesive applying mechanism comprising a conveyor to convey carton blanks, an adhesive applying roll arranged over the path of the conveyor, the adhesive applying roll being provided with a segment adapted to contact a blank on the conveyor, a pressure roll arranged beneath the conveyor, the pressure roll being provided with a segment adapted to contact the under side of the carton blank, drive means for the adhesive applying roll, drive means for the pressure roll, a clutch in the pressure roll drive means, and a roller arranged over the conveyor, the roller being adapted to move downwardly in the absence of a carton blank on the conveyor, and means connecting the roller to the clutch to disengage the clutch upon downward movement of the roller.

7. Adhesive applying apparatus comprising a table having a pair of parallel slots, conveyor chains traveling in the slots, means on the conveyor chains to engage a blank to propel it along the table, the table having an opening therein, a pressure roll under the opening, an adhesive applying roll over the opening, the surfaces of the rolls being spaced from the table, segments carried by each of the rolls of such size that they contact the opposite sides of a carton blank traveling along the table, means for rotating the rolls to bring the segments into contact with the surfaces of the blank, a clutch

in the drive means controlled by the feed of blanks of the pressure roll, and means for disengaging the clutch in the absence of a blank on the conveyor.

8. Adhesive applying apparatus comprising a table having a pair of parallel slots, conveyor chains traveling in the slots, means on the conveyor chains to engage a blank to propel it along the table, the table having an opening therein, a pressure roll under the opening, an adhesive applying roll over the opening, the surfaces of the rolls being spaced from the table, segments carried by each of the rolls of such size that they contact the opposite sides of a carton blank traveling along the table, means for rotating the rolls to bring the segments into contact with the surfaces of the blank, a clutch in the drive means of the pressure roll, rollers arranged over the conveyor and normally retained in raised position by contact with a blank on the conveyor, and a connection between the rollers and the clutch to disengage the clutch upon downward movement of the rollers due to the absence of a blank on the conveyor.

9. Adhesive applying apparatus comprising a table having a pair of parallel slots, conveyor chains traveling in the slots, means on the conveyor chains to engage a blank to propel it

along the table, the table having an opening therein, a pressure roll under the opening, an adhesive applying roll over the opening, the surfaces of the rolls being spaced from the table, segments carried by each of the rolls of such size that they contact the opposite sides of a carton blank traveling along the table, drive means to rotate the pressure roll and the adhesive applying roll to bring the segments into contact with the surfaces of the blank, a clutch in the pressure roll drive means, and control mechanism on the table connected to the clutch, said control mechanism being biased toward a position to disengage the clutch but being normally retained in an inoperative position by the presence of a carton blank on the table.

along the table, the table having an opening therein, a pressure roll under the opening, an adhesive applying roll over the opening, the surfaces of the rolls being spaced from the table, segments carried by each of the rolls of such size that they contact the opposite sides of a carton blank traveling along the table, drive means to rotate the pressure roll and the adhesive applying roll to bring the segments into contact with the surfaces of the blank, a clutch in the pressure roll drive means, and control mechanism on the table connected to the clutch, said control mechanism being biased toward a position to disengage the clutch but being normally retained in an inoperative position by the presence of a carton blank on the table.
